HOUSING FOR AN INDICATING INSTRUMENT

Thomas L. Faul, Skaneateles, N.Y., assignor to Aquamarine Mfg. Limited, Toronto, Ontario, Canada

Filed Dec. 2, 1963, Ser. No. 77,640

Term of patent 14 years

(Cl. D52—6)

FIG. 1

FIG. 2

FIGURES 1 and 2 are perspective views of the housing for an indicating instrument from opposite ends thereof showing the top side and under side respectively of the housing with the dial portion of an instrument mounted within the housing shown in broken lines for illustrative purposes only.

The rear of the housing is hollowed out to follow the contour of the face of the housing shown in FIGURES 1 and 2.

I claim:

The ornamental design for a housing for an indicating instrument, as shown and described.
